UNITED STATES PATENT OFFICE.

THÉOPHILE SCHLOESING, OF PARIS, FRANCE.

PROCESS FOR REMOVING NICOTINE FROM TOBACCO TO ANY DESIRED EXTENT WITHOUT DESTROYING ITS AROMA.

Application filed January 26, 1925, Serial No. 4,937, and in France May 30, 1924.

This invention relates to a process for removing nicotine from tobacco to any desired extent without destroying its aroma.

It is known that ammonia displaces nicotine and that steam can carry off nicotine vapour.

The said process makes use of these facts but in a new method justifying both theory and practice.

10 It has already been proposed to remove nicotine from tobacco by moistening the tobacco with ammonia and afterwards subjecting it to the action of steam.

15 It has also been proposed to employ steam at a pressure lower than atmospheric, that is to say, a temperature below 100°, with a view to decreasing the loss of the aromatic constituents in the tobacco.

20 Experiments have shown that if the tobacco to be treated is moistened with a solution of ammonia prior to its being subjected to the action of steam, the nicotine can only be removed by the steam to a certain degree and this is true even when a large amount 25 of the ammoniacal solution is employed. This can be explained theoretically and verified by experiment. When steam is passed over tobacco treated with an ammoniacal solution, the treated tobacco carries to start

30 with free ammonia in excess. There remains present in the tobacco ammonia salts and nicotine. There is a reciprocal displacement of ammonia and nicotine; the nicotine decomposes in part the ammonia salts, freeing the ammonia with the formation 35 of nicotine salts and in consequence there is in the tobacco in the form of salts a certain proportion of nicotine which is not driven off by the steam. This proportion is substantial. It may easily be of the order of 50 or 40% even when with the object of reducing is a great deal of steam has been passed over (5 to 10 times the weight 40 of the tobacco). Even if the tobacco is treated with fresh additions of ammonia, it is not possible to remove all of the nicotine without prolonged action and in order to accurately determine the condition of the treated tobacco, it is necessary not only to

45 ascertain if appreciable quantities of alkaloid are no longer evolved, but also to ascertain directly the quantity of nicotine in the treated tobacco.

50 On the other hand, according to experi-

mental results the more steam is employed, 55 the more the tobacco is deprived of its aromatic constituents, comprising under this term the various substances more or less volatile which contribute to its taste and aroma; if only to avoid this danger the 60 quantity of steam used must be restricted as much as possible.

According to this invention a current of a mixture of steam and gaseous ammonia is passed over the tobacco which is placed in a 65 container R (see the accompanying drawing) it being unnecessary previously to moisten the tobacco with ammonia. An appreciable ammoniacal pressure is maintained in the medium during the whole treatment 70 (by a permanent adjunction of gaseous ammonia) which prevents the formation of nonvolatile nicotine salts and suppresses any limit to the elimination of the alkaloid. Nicotine is constantly displaced by the ammonia 75 and carried off by the steam as it is set free. The elimination of the nicotine from the tobacco may be considerable and if really desired may be complete; it may be carried out to any degree that is desired 80 according to the quantity of steam mixed with the ammonia that is passed over.

It has been found that if the gaseous ammonia is maintained at a proportion of a certain order when mixed with steam the 85 elimination of the nicotine from the tobacco only depends on the quantity of steam employed. This suitable proportion of gaseous ammonia may be varied between wide limits, for example, between 25 grams or 90 even less and 160 grams or even more of gaseous ammonia to 1 kilogram of steam. It is this circumstance which gives great flexibility to the process. It is not necessary to regulate with care and exactness the 95 proportion of gaseous ammonia in the steam. The steam passed over has only to be measured by condensing it and by ascertaining the volume of water resulting from the condensation, and a practical measurement 100 of the nicotine extracted can thus be obtained without minute observation of analysis.

Due to the constant presence of gaseous ammonia the amount of which may vary between wide limits, as mentioned above the elimination of the nicotine from the tobacco is both quicker and more complete with a

quantity of steam much less than that which must be employed, if a permanent ammoniacal pressure is not maintained.

With this moderate use of steam there only results a very small loss of flavour and aroma in the tobacco. It is so small that it is not necessary to seek to restrict it in order to keep the temperature of the operation down, so that the treatment with the steam and ammonia may be carried out at atmospheric pressure at 100° C.; it is much more simple in operation and in the apparatus used than to operate at a lower temperature under reduced pressure.

15 Another method may be employed to reduce the loss of flavour to an insignificant extent. This consists in recovering the major portion of the small quantities of aromatic constituents which have been separated from the treated materials and adding them to the mixture of steam and ammonia which is again passed over the tobacco.

After passing over the tobacco, the steam 25 is condensed in the condenser D with the nicotine, the ammonia and the small quantities of aromatic constituents driven off. The liquor produced by condensation is thus a solution of ammonia and nicotine containing small quantities of aromatic constituents. It arrives in a container A where by means of a pipe 3 with upwardly directing openings it is placed in intimate contact with a solvent such as petroleum which entirely absorbs the nicotine. The ammoniacal solution being heavier than the solution occupies the bottom of the container and passes out therefrom through pipe 2 together with the aromatic constituents. The 30 solvent in the upper part of the container passes out through pipe 1 to a container B where it is completely freed from its dissolved nicotine by putting it in contact with an acid such as sulphuric, and then returns 35 to A to be charged afresh with nicotine; it circulates continually from A to B and from B to A. From B is extracted the nicotine salt (sulphate for example) formed, separated from the solvent. But the ammonia 40 being slightly soluble in the petroleum, the steam condensate abounds to the petroleum together with nicotine, a little ammonia and there is obtained in B, owing to the action of the sulphuric acid on the petroleum containing 45 nicotine and a little ammonia, not only nicotine sulphate but ammonium sulphate. This latter is almost insoluble in the concentrated solution of nicotine sulphate which is formed, and at the end of a certain 50 time it causes the solution to become pasty, thus producing an appreciable hindrance in the action. It is necessary to free the petroleum or other solvent of ammonia that it 55 contains by a method hereinafter described; 60 which solvent has been used to cover the

nicotine extracted from the tobacco before returning it to A.

The ammoniacal solution from A is, for example, led to a container C where it is vaporized; the vapours coming off again being passed over the tobacco after the addition of a small quantity of fresh ammonia necessary to compensate the losses in gaseous ammonia and in the water. The ammoniacal solution coming from A can also be passed into apparatus such as a plate distiller where it flows in an opposite direction to the steam, giving up all its ammonia to the steam and at the same time its aromatic constituents; it passes out as water free from ammonia.

A mixture of steam and gaseous ammonia and aromatic constituents is again formed and again used to treat the tobacco. The latter should naturally be protected against cooling so that condensation in the parts in contact with the walls is avoided; this may be achieved, for example, by making the steam pass, before coming into contact with the tobacco, between the container containing the materials and a casing coated externally with nonheat-conducting material. The tobacco is ready for common use when removed from the container.

It should be remarked that it is necessary that the nicotine should be removed from the ammoniacal solution coming from A and entering C. If nicotine remains in this solution, it goes out of C with the steam and the gaseous ammonia; a mixture of steam and gaseous ammonia containing nicotine vapour would then be made to pass over the tobacco and then only a partial removal of the nicotine from the tobacco could be obtained, a feeble pressure of nicotine vapour preventing the removal of this alkaloid; frequently the tobacco would be enriched in nicotine.

The gaseous ammonia follows a closed cycle: container C (a boiler or distiller), tobacco container R, condenser D, container A where the ammonia separates from the nicotine, container C, etc. The aromatic constituents accompany the gaseous ammonia. The tobacco only fixes small quantities of ammonia.

The nicotine extracted from the tobacco passes out as a salt, for example, a sulphate, and constitutes a valuable by-product.

The tobacco after treatment is milder but still contains its aroma. It no longer produces any irritation of the throat and may be used without inconvenience by persons on whom the action of nicotine is injurious.

It has been stated above that it is necessary before removing the solvent from A to remove any ammonia dissolved in it.

Various processes can be utilized to effect this elimination of ammonia contained in the solvent. One means consists in passing the

- solvent upwards through water, preferably in more or less small streams or bubbles. If the contact of the two liquids is sufficient, the water retains all the ammonia with a little nicotine. This washing water may be renewed gradually by making it circulate in the opposite direction to the petroleum in such a manner that the latter is found completely deprived of its ammonia.
- If the water carries with it an appreciable quantity of nicotine, it can be made to enter into the cycle of operations above described.
- In this process of eliminating the ammonia the water may be saturated with a salt such as sodium chloride for example; such a liquid has the advantage of dissolving less nicotine than pure water, while dissolving the ammonia nearly as well.
- Another method which is very simple and particularly good for the removal of the ammonia from the petroleum (or other nicotine and ammonia solvent) consists in bringing the petroleum in intimate contact with gas such as air; for example, the gas could be caused to bubble into the petroleum, or the petroleum could be brought to a finely divided state by causing it to fall in thin sheets or little drops. As here shown, the petroleum enters a purifying device E and is caused to flow over solid materials of regular or irregular shape, for instance, pebbles or the like, and a current of air is caused to pass over the petrol thus divided. The current of air would take with it very readily all the ammonia without taking off at the same time an appreciable quantity of nicotine vapour. The ammonia led off by the gaseous current is easily recovered by any known means, for example, by passing the gaseous current in a container where it is put into contact with an acid.
- What I claim is:
1. A process for removing nicotine from tobacco without destroying the aroma of the latter, which consists in circulating a mixture of steam and gaseous ammonia through the tobacco in a closed system, removing the entrained nicotine from said mixture, and again passing the mixture over the tobacco.
  2. A process for removing nicotine from tobacco, consisting in treating tobacco with a mixture of steam and gaseous ammonia, condensing said mixture, removing the nicotine from said condensate by means of a solvent, vaporizing said condensate, and reintroducing said vaporized condensate and said solvent in the cycle of operations.
  3. A process for removing nicotine from tobacco, consisting in treating tobacco with a mixture of steam and gaseous ammonia, condensing said mixture, removing the nicotine from said condensate by means of a solvent, recovering the nicotine from said solvent, removing the ammonia from said solvent, vaporizing said condensate and reintroducing said vaporized condensate and said solvent in the cycle of operations.
  4. A process for removing nicotine from tobacco, consisting in treating tobacco with a mixture of steam and gaseous ammonia, condensing said mixture, removing the nicotine from said condensate by means of a solvent, recovering the nicotine from said solvent, treating said solvent in a finely divided state with a current of air for removing the ammonia therefrom, vaporizing said condensate, and reintroducing said vaporized condensate and said solvent in the cycle of operations.
  5. A process for removing nicotine from tobacco without destroying the aroma of the latter, which consists in circulating a mixture of steam and gaseous ammonia through the tobacco, the proportion of ammonia gas in the mixture being substantially 25 grams to one kilogram of steam, removing the nicotine from the mixture, and again passing the mixture over the tobacco.
  6. A process for removing nicotine from tobacco without destroying the aroma of the latter, which includes circulating a mixture of steam and gaseous ammonia through the tobacco, entraining the removed nicotine in petroleum and returning the ammonia gas, steam and aromatic constituents to the tobacco.
  7. A process for removing nicotine from tobacco without destroying the aroma of the latter, which includes the steps of passing a mixture of steam and gaseous ammonia through the tobacco, introducing this mixture with the constituents removed from the tobacco into petroleum, drawing off the petroleum and nicotine, removing the nicotine from the petroleum, purifying the petroleum, and returning the same to a circuit in which the steam and ammonia gas circulate.
